FOLDING CHAIR

Walter E. Nordmark, Grand Rapids, Mich., assignor to American Seating Company, Grand Rapids, Mich., a corporation of New Jersey

Application February 28, 1952, Serial No. 273,871

6 Claims. (Cl. 155—142)

1

The present invention relates to folding chairs and more particularly to steel folding chairs of the inverted Y-type.

The primary objects of the invention are to provide such a folding chair which is "non-jack-knifing," that is, a chair which will not tend toward collapsing when the occupant thereof shifts his weight too far rearwardly, and in general to provide such a folding chair which is efficient in use and reasonably economical in manufacture.

An illustrative embodiment of the invention is shown in the accompanying drawings, wherein:

Figure 1 is a perspective view of an inverted Y-type steel folding chair in unfolded position;

Figure 2 is a side elevational view of the same;

Figure 3 is a fragmentary horizontal sectional view of parts of the same taken on line 3—3 of Figure 2;

Figure 4 is a fragmentary rear elevational view of the same;

Figure 5 is a side elevational view of the chair in folded condition;

Figure 6 is an enlarged, fragmentary, central vertical sectional view of parts of the chair, shown in folded condition in full lines and in partially unfolded condition in broken lines; and

Figure 7 is a similar view showing the parts in partially unfolded condition in broken lines and in fully unfolded position in full lines.

Referring now in detail to this drawing, wherein like parts of the structure are indicated by the same numerals in the several views, the chair there shown generally comprises an inverted U-shaped tubular metal front frame providing spaced front legs 10 for the chair and an upper bight portion 11 in which is secured a back panel 12, spaced tubular metal rear legs 13 having their upper ends hingedly connected as by means of hinge straps 14 to the front legs 10, and a seat 15 here shown of plywood or the like mounted on and between the front and rear legs of the chair.

The front legs 10 are connected to each other by means of an upper tie-bar or rod 16 located at about the seat level and a lower tie-bar or rod 17, and the rear legs 13 are similarly connected by means of an upper tie-bar or rod 18 located rearwardly of the seat, and a lower tie-bar or rod 19.

The seat proper is mounted upon spaced seat arms 20 which extend forwardly-rearwardly at the opposite undersides of the seat, said arms being provided with vertical flanges 21 and with inwardly extending horizontal flanges 22 to which the seat is secured as by means of rivets 23. The vertical flanges 21 are provided with forward slots

2

24 which slope downwardly and then forwardly in the unfolded position of the chair. The upper tie-bar 16 which connects the front legs of the chair extends through these slots 24, and the seat 5 is thus pivotally and slidably mounted on the front legs 10. Rear slots 25 are also provided in the vertical flanges 21 of the seat arms 20, and these slots 25 slope forwardly and slightly upwardly in the unfolded position of the chair. Curved rear links 26 have their rearward ends 10 pivotally connected at 27 to the rear legs 13 below the upper tie-bar 18, and straight front links 28 have their forward ends pivotally connected to the upper tie-bar 16. The rearward ends of the 15 front links 28 and the forward ends of the rear links 26 are pivotally connected together and pivotally and slidably connected to the seat arms 20 by means of pin-and-slot connections comprising pins 29 extending through apertures in 20 the links and through the rear slots 25 in the seat arms. Both ends of these pins 29 are riveted over to secure these parts in assembly.

The rearward end portions of the seat arms 20 25 extend rearwardly of the seat 15 at the opposite rear corners thereof, and are shaped to provide hooks 30 which extend rearwardly, then upwardly and then forwardly in the unfolded position of the chair. The upper forward edges of these hook portions of the seat arms 20 are rearwardly-downwardly sloping to provide cam surfaces 31 30 the purpose of which is described hereinafter.

Operation

The chair being in its folded position shown in 35 full lines in Figures 5 and 6, it is unfolded by pressing downwardly on the front edge of the seat. This movement is transmitted to the rear legs through the rear links 26 which are thus spread rearwardly from the front legs as the seat 40 is lowered. When this unfolding movement has progressed as far as the broken line representations shown in Figures 6 and 7, the cam surfaces 31 on the seat arms 20 bear against the tie-bar 18, and in the final unfolding movement the seat 45 is thereby cammed forwardly so that the hooks 30 engage around the tie-bar 18 thus to prevent either raising or lowering movement of the rearward edge of the seat. The chair is thus positively prevented from "jack-knifing" when occupied.

When the chair is to be folded, it is tipped slightly forwardly to raise the rear legs off the floor. The front edge of the seat is then lifted, and the rearward component of the force exerted on the seat slides the seat rearwardly so that the hooks 30 of the seat arms 20 are disengaged from

the tie-bar 8 thus permitting full folding of the chair.

While but one specific embodiment of the invention is shown in the accompanying drawings and hereinbefore described, it will be understood that numerous details may be altered or omitted without departing from the spirit of the invention as the same is defined by the following claims.

I claim:

1. A folding chair comprising spaced front legs, spaced rear legs having their upper ends hingedly connected to the front legs, a seat pivotally and slidably mounted between said front legs, a link pivotally connected to one of the rear legs and having a pin-and-slot connection with the seat, a stop on one of said rear legs, a hook extending from the rear of the seat rearwardly, then upwardly and then forwardly, and cam means on the seat engageable with the stop on said rear leg for sliding the seat forwardly during the final unfolding of the chair thus to engage said hook around said stop to prevent either raising or lowering movement of the rearward edge of the seat in the unfolded position of the chair.

2. A folding chair comprising spaced front legs, spaced rear legs having their upper ends hingedly connected to the front legs, a seat pivotally and slidably mounted between said front legs, a link pivotally connected to one of the rear legs and having a pin-and-slot connection with the seat, a tie-bar connecting said rear legs rearwardly of the seat, a hook extending from the rear of the seat rearwardly, then upwardly and then forwardly, and cam means on the seat engageable with the tie-bar on said rear leg for sliding the seat forwardly during the final unfolding of the chair thus to engage said hook around said tie-bar to prevent either raising or lowering movement of the rearward edge of the seat in the unfolded position of the chair.

3. A folding chair comprising spaced front legs, spaced rear legs hingedly connected to the front legs, a seat pivotally and slidably mounted between said front legs, links having their rearward ends pivotally connected to the rear legs and having pin-and-slot connections with the seat at their forward ends, a tie-bar connecting said rear legs rearwardly of the seat, hooks extending from the rear corners of the seat rearwardly, then upwardly and then forwardly, and cam means on the seat engageable with the tie-bar for sliding the seat forwardly during the final unfolding of the chair thus to engage said hooks around said tie-bar to prevent either raising or lowering movement of the rearward edge of the seat in the unfolded position of the chair.

4. A folding chair comprising spaced front legs, spaced rear legs having their upper ends hingedly connected to the front legs, rear links having their rearward ends pivoted to the rear legs, front links having their forward ends pivotally connected to the front legs and having their rearward ends pivotally connected to the forward ends of the rear links, a seat having its opposite sides pivotally and slidably mounted on the pivotal connections between the front legs and the front links and also pivotally and slidably mounted on the pivotal connections between the front

links and the rear links, a stop on one of the rear legs rearwardly of the seat, and a hook extending from the rear of the seat rearwardly, then upwardly and then forwardly, the seat being slideable forwardly on its mountings during the final unfolding of the chair so that said hook engages around the stop on said rear leg to prevent either raising or lowering movement of the rearward edge of the seat in the unfolded position of the chair.

5. A folding chair comprising spaced front legs, spaced rear legs having their upper ends hingedly connected to the front legs, rear links having their rearward ends pivoted to the rear legs, front links having their forward ends pivotally connected to the front legs and having their rearward ends pivotally connected to the forward ends of the rear links, a seat having its opposite sides pivotally and slidably mounted on the pivotal connections between the front legs and the front links and also pivotally and slidably mounted on the pivotal connections between the front links and the rear links, a tie-bar connecting the rear legs of the chair rearwardly of the seat, and a pair of hooks extending from the opposite rear corners of the seat rearwardly, then upwardly and then forwardly, the seat being slideable forwardly on its mountings during the final unfolding of the chair so that said hooks engage around said tie-bar to prevent either raising or lowering movement of the rearward edge of the seat in the unfolded position of the chair.

6. A folding chair comprising spaced front legs, spaced rear legs having their upper ends hingedly connected to the front legs, rear links having their rearward ends pivoted to the rear legs, front links having their forward ends pivotally connected to the front legs and having their rearward ends pivotally connected to the forward ends of the rear links, a seat having its opposite sides pivotally and slidably mounted on the pivotal connections between the front legs and the front links and also pivotally and slidably mounted on the pivotal connections between the front links and the rear links, a tie-bar connecting the rear legs of the chair rearwardly of the seat, and a pair of hooks extending from the opposite rear corners of the seat rearwardly-downwardly, then upwardly and then forwardly, the rearwardly-downwardly extending portions of said hooks camming against the tie-bar during the final unfolding of the chair thus to slide the seat forwardly so that said hooks engage around said tie-bar to prevent either raising or lowering movement of the rearward edge of the seat in the unfolded position of the chair.
